UNITED STATES PATENT OFFICE.

WALTER W. SMITH, OF GILLETT, WISCONSIN.

SECTIONAL FLANGE.

1,035,254.

Specification of Letters Patent. Patented Aug. 13, 1912.

Application filed December 6, 1911. Serial No. 664,229.

To all whom it may concern:

Be it known that I, WALTER W. SMITH, a citizen of the State of Wisconsin, United States of America, residing at Gillett, Wisconsin, have invented certain new and useful Improvements in Sectional Flanges, of which the following is a specification.

The invention relates to cooping, and more particularly to improvements in a clamping device or chuck for holding the staves of a bucket in proper relation, for turning the outer surface of the bucket and thereby evening the surface thereof, prior to applying the hoops thereto.

An object of the invention is to provide an improved chuck from which the bucket may be easily taken, after the same has been turned and after a hoop, or hoops, have been applied.

A further object of the invention is to provide a chuck of the character described which may be applied to and used in connection with either a vertical or a horizontal lathe of ordinary construction.

With these and other objects in view, the invention consists in the details of construction and in the arrangement and combination of parts to be hereinafter more fully described and claimed.

In describing the invention in detail, reference will be had to the accompanying drawings forming part of this specification, wherein like characters designate corresponding parts in the several views, in

which—

Figure 1, is an elevation view of my improved chuck, having a number of staves clamped therein, in position for being turned; Fig. 2, is a horizontal section taken on the line 2—2 of Fig. 1; Fig. 3, is a vertical sectional view taken on the line 3—3 of Fig. 2; and Fig. 4, is a fragmental vertical sectional detail, taken on the line 4—4 of Fig. 2, and showing the manner of raising and lowering the segments.

Referring more particularly to Figs. 3 and 4, for the details, A is a spindle having a collar B shrunk thereon; its end C being screw-threaded. Rotatably seated upon the spindle, is a brim-engaging disk, or main disk, which will hereinafter be known as the rabbeted disk, and this disk has a peripheral rabbet d therein. An eccentrically apertured disk E is concentric to the disk D and to the spindle A and is fixed to the disk D by means of stay-bolts F. A sleeve G is rotatably mounted on the spindle, and has at

one end a radial flange g containing apertures g¹ through which the stay-bolts F extend, and also having apertures g², and having lugs g³ adjacent to the apertures g². Links H are pivoted to said lugs at g⁴. Each alternate link H being slotted at one end as at h for a purpose hereinafter explained.

The disk E has apertured lugs e thereon, and through the apertures thereof extend pivots e¹ to which are connected the segmental plates I. These plates are rabbeted on their arcuate edges as shown at i, for a purpose hereinafter shown. The plates I have apertured lugs i¹ through which pivots i² extend; and to each of these pivots is connected an end of a link H. A nut J is screw-threaded onto the portion C, of the spindle, and is connected to sleeve G by means of a union coupling device as illustrated at R which operates sleeve G and consequently all parts connected therewith as the nut I is turned one way or the other. A collar K is fixed on the spindle A in proximity with the disk D.

In Fig. 1, the chuck is represented as having staves L secured in position for the turning operation; and it may be noted that, with this object in view, the outer surfaces of the staves extend beyond the peripheries, respectively, of the main disk and the plates I. The disk D is provided with a hub M which is designed to have frictional contact with the collar B.

In operation, the chuck is permanently fixed to a special lathe. For best and only good service, it must be so arranged that there be no obstruction adjacent to the threaded portion C so that after the bucket has been turned, the plates may be caused to assume the position shown in dotted lines, Fig. 4; whereupon, the bucket may be moved in its axial direction and removed from the chuck over the nut J and the threaded portion C. I have indicated only a sufficient portion of the actuating mechanism as will suffice to show the connection of my improved chuck therewith, and this actuating mechanism comprises a band wheel N, secured on the shaft A, and adapted to be connected, by friction-belt transmission, with any proper source of power. The shaft A is journaled in bearings O, and is provided with a thrust-preventing collar P, the sleeve B also preventing thrust motion of the shaft. In applying the staves to the chuck they are, of course, first properly sized and are then fitted within the rabbets

d and *i* as shown in Fig. 1. By turning nut *J*, which has union coupler *S* and *R* attached, as before explained, with sleeve *G* forming part of the coupling, sleeve *G* is drawn toward end *C* of spindle *A*, thus drawing disk *g* in the same direction and operating links *H* which force the sections of flange *I* into position as shown in dotted lines in Fig. 4. When in closed position, the sections of flange *I* fit closely together at their sectional edges, forming one complete and solid flange. Each alternate link *H* is slotted at the opposite end from its connection with flange *I*, thus compelling the unslootted links to move its section of the flange out of the way of its neighbors before the other begins to move. The pail, bucket or tub, being turned, is then removed over the nut *J*, and another is inserted and clamped into position, and the motion of the nut is reversed to firmly clamp the work into position. After being chucked, the spindle is rotated, thereby rotating the bucket which may have its exterior surface evened by the use of any proper tools or means. After the surface of the bucket has been properly evened, hoops may be applied in the usual way and the bucket removed in the manner described in the foregoing. It is obvious that in order to raise the plates into the dotted line position shown in Fig. 4, certain of the plates must be raised before other of the plates rise, in order that their radial edges shall not conflict, and to provide for this condition, the pivots *g*⁴, in certain of the lugs *g*³ are slideable in the slots *h*; and it is obvious that while the non-slootted links are being moved, the slotted links will remain at rest until the plates *I*, which are connected to the non-slootted links, have been moved sufficiently to allow the alternate plates to be moved without interfering therewith. The plates connected with the slotted links are not moved until the pivots *g*⁴ have traveled the length of the slots *h* and contact the end thereof.

The invention is obviously susceptible of numerous modifications of construction without departure from the spirit and scope of the invention as shown and hereinafter claimed, and is not confined to the manufacture of buckets; being obviously applicable in the manufacture of tubs, kegs, barrels, hogsheads and the like.

I claim:

1. In a coopering device, a stave chuck comprising a rotatable spindle, a rabbeted disk on the spindle, a flanged sleeve slideable longitudinally on the spindle, an eccentrically apertured disk in concentric and fixed relation to the rabbeted disk, rabbeted segmental plates pivoted to the apertured disk,

links extending through the apertured disk and pivotally connecting with the flange of the sleeve and with said segmental plates, the rabbeted portions of said rabbeted disk and of the segmental plates being adapted to receive the respective ends of a set of bucket staves, and means coacting with the spindle and with the flanged collar and the links, for tightening the said rabbeted portions upon the bucket staves.

2. In a coopering device, a stave chuck comprising a rotatable spindle, a rabbeted disk rotatable on the spindle, a flanged sleeve slideable longitudinally and rotatable on the spindle, a friction disk coacting with the rabbeted disk for normally preventing rotation of the latter, relative to the spindle, an eccentrically apertured disk in concentric and fixed relation to the rabbeted disk, rabbeted segmental plates pivoted to the apertured disk, links extending through the apertured disk and pivotally connecting with the flange of the sleeve and with said segmental plates, the rabbeted portions of said rabbeted disk and of the segmental plates being adapted to receive the respective ends of a set of bucket staves, and means coacting with the spindle and with the flanged collar and the links, for tightening the said rabbeted portions upon the bucket staves.

3. In a coopering device, a chuck comprising a spindle, a rabbeted disk on the spindle, a second disk concentric with the spindle and in fixed relation to the rabbeted disk, segmental rabbeted plates pivoted on said second disk, the rabbeted portions of the plates and of the rabbeted disk being adapted to receive a set of staves, a nut threaded on the spindle, and means coacting with the nut and spindle and the said second disk for tightening the rabbeted disk and the rabbeted plates upon the staves.

4. In a coopering chuck, a disk having a rabbeted periphery, a spindle rotatable with the disk, rabbeted segmental plates arranged concentrically with the rabbeted disk and normally on a plane parallel thereto, the rabbeted portions of the disk and of the plates being adapted to receive a set of bucket staves, means for tightening the rabbeted portions of the plates upon the staves and for alternately moving them out of their normal plane into collapsed position, whereby the staves may be removed in unison after being formed and secured into the form of a bucket.

In testimony whereof I affix my signature in the presence of two witnesses.

WALTER W. SMITH.
